2 SHEETS—SHEET 2.

UNITED STATES PATENT OFFICE.

HOWARD H. CRAWFORD, OF DETROIT, MICHIGAN, ASSIGNOR TO DETROIT MOTOR APPLIANCE COMPANY, OF DETROIT, MICHIGAN, A CORPORATION OF MICHIGAN.

RADIATOR-SHIELD.

1,352,184.

Specification of Letters Patent.

Patented Sept. 7, 1920.

Application filed September 18, 1916. Serial No. 120,863.

To all whom it may concern:

Be it known that I, HOWARD H. CRAWFORD, a citizen of the United States of America, residing at Detroit, in the county of Wayne 5 and State of Michigan, have invented certain new and useful Improvements in Radiator-Shields, of which the following is a specification, reference being had therein to the accompanying drawings.

10 The invention relates to temperature controlling devices for radiators, and has particular reference to constructions adapted for use either in the original installation or as a replacement.

15 In the present state of the art, radiators have been provided with shutters for controlling the volume of air passing through the radiator core. These shutters have, however, been mounted as adjuncts to the 20 radiator, and are objectionable in that they mar the appearance and change the standard lines of the machine. It is the object of the present invention to avoid this objection, and to this end the invention comprises the 25 novel combination of the shutters with the shell which incloses the radiator core.

Heretofore radiators have been provided with pressed sheet-metal shells which form the outer finish, completely surrounding the 30 radiator core but not a structural part thereof. Such shells are usually provided with a front face concealing the top and bottom headers and edges of the core, but having an open panel for exposing the air 35 and water tubes. With my improved construction I make use of a shell of the same general design but extended outward sufficiently in advance of the front face of the air and water tubes to receive and provide

40 clearance for the operation of shutters. The shutters are mounted within the shell and are preferably so arranged that in closed position they present a substantially flat face parallel to the plane of the front face 45 of the shell, while in opened position they are arranged at right angles and fully expose the air and water tubes.

In the drawings:

Figure 1 is a front elevation of the construction embodying my invention;

Fig. 2 is a perspective view showing the inner side of the shell and shutters mounted therein in closed position;

Fig. 3 is a horizontal section; and

Fig. 4 is a vertical section.

My improved construction is applicable either to automatic temperature control devices, in which the shutters are opened and closed by a thermostat, or to a manually operable regulator. In detail, the construction comprises a shell A, preferably formed of pressed sheet-metal, and having the integral side flanges B and front face C, the latter having the open panel D. On the opposite sides of the front and on the inner 60 face thereof are mounted bearings E, preferably in the form of a channel bar having a fiber filler F, apertured for receiving the pintles G of the shutters H. These pintles are preferably the end portions of hinge 65 rods I extending the full length of the shutters and preferably at one edge thereof which is looped around the rod, while the opposite edge is adapted to underlap the adjacent rod. Each shutter is also provided with a lug J having a pindle K engaging an actuating bar L similar in construction to the bars E. M is a bell-crank lever fulcrumed upon the inner side of the shell and connected by a pivotal link N 80 with the bar L.

Where the construction is designed for a replacement, the shell may be formed either of the same lines as the original or of changed lines, but in each case the depth is 85 increased a sufficient amount to provide for the operation of the shutters in front of the core. In the same manner, where the device is designed for original installation increased depth of shell is provided, but otherwise the lines remain standard. The whole construction is independent of the core and can be removed or replaced without disturbing the latter, while the space between the sides of the shell and the core provides 90 clearance for the operating mechanism.

Any suitable construction of radiator core may be employed, such as indicated in dotted lines in Figs. 3 and 4.

What I claim as my invention is:

1. The combination with a radiator core, of a shell forming the regular outer finishing piece for said core, having an open panel for exposing the air and water tubes and being extended beyond the front plane of the 105 same, and shutters mounted and operable within said shell between the front face thereof and the front face of the core.

2. The combination with a radiator core, of a shell forming the regular outer finish- 110

ing piece for said core, having its front face in a plane spaced from the front face of the core, shutters mounted within said shell and operable in the space between the front face thereof and the front face of the core, and 5 operating mechanism for said shutters arranged between the side of the shell and the side of the core.

3. The combination with a radiator core, 10 of a shell forming the regular outer finishing piece for said core formed of pressed sheet-metal, having a front face with an open panel and sides extending rearward therefrom, the depth of said sides being sufficient to space the front face from the front 15 face of the core, and shutters mounted on the inner face of the front of said shell adapted in one position to close said open panel and also to swing in the space between 20 the shell and core to open said panel.

4. The combination with a radiator core, of a shell forming the regular outer finishing piece for said core formed of pressed sheet-metal having a front face with an open panel and side flanges extending rearward therefrom, the depth of said sides being sufficient to space the plane of the front 25 from the front plane of the core, bearings mounted on the inner face of the sides of the 30 front, shutters journaled in said bearings and extending across said open panel, and a common actuating means for said shutters, by which they may be simultaneously opened and closed in the space between the front 35 faces of the shell and core.

5. The combination with a radiator core, of a shell forming the regular outer finishing piece for said core, extending forward thereof, and shutters controlling the air to 40 said core, inclosed and operable within the forward extension of said shell.

6. The combination with a radiator core, of a shell forming the regular outer finishing piece for said core, said shell being extended forwardly beyond the core and being 45 provided at its front with an open panel for exposing the air and water tubes, and means for regulating the flow of air through the core mounted and operable 50 within said shell and extending between the front face thereof and the core.

7. The combination with a radiator core, of a shell forming the regular outer finishing piece for said core and having its front 55 face in a plane spaced forwardly from the

core, mechanism for regulating the flow of air through the core mounted within said shell and operable within the space between the front face thereof and the core, and operating means for said mechanism arranged 60 between a side of the shell and the adjacent sides of the core.

8. The combination with a radiator core, of a shell forming the regular outer finishing piece for said core, having its front face 65 in a plane spaced forwardly from the core, shutters mounted within said shell and operable in the space between the front face thereof and the core, an actuating strip connecting said shutters, and a bell-crank 70 mounted between the core and a side of the shell, having actuating engagement with said strip.

9. The combination with a radiator core, of a shell forming the regular outer finishing 75 piece for said core, formed of pressed sheet-metal and incasing the core and sides and top thereof, and having a front face with an open panel, the depth of the sides of the shell being sufficient to space the front thereof forwardly from the core, shutters extending across said open panel within the front portion of said shell, a pair of bearing strips for said shutters mounted interiorly upon the front of the shell respectively at each 80 side of the panel, and a common actuating means for said shutters.

10. The combination with a radiator core, of a shell forming the regular outer finishing piece for said core, formed of pressed 90 sheet metal having a front face with an open panel and side flanges extending rearwardly therefrom, the depth of said sides being sufficient to space the plane of the front of the shell from the front plane of the core, and 95 shutters mounted on the inner face of said shell adapted in one position to close said open panel and also to swing in the space between the shell and the core to open said panel, the shutters in their open position 100 presenting a front edge having a reinforcement.

11. The combination with a radiator core of an automobile, of a shell forming the regular outer finishing piece for said core, and 105 shutters carried by said shell for controlling the passage of air through said shell to the radiator core.

In testimony whereof I affix my signature.
HOWARD H. CRAWFORD.
